SIGNORS TO WACHUSSETT SHIRT COMPANY, OF LEOMINSTER, MASSACHUSETTS, A
CORPORATION OF MASSACHUSETTS.

SOFT COLLAR.

Application filed June 21, 1927. Serial No. 200,471.

This invention relates to a soft collar and the principal object thereof is to provide means in a practical and convenient form for stiffening the points of the collar. The invention also involves this means in such form that it will not cause any bunching of the material at the corners or edges and will not have any free inner edge which would buckle, roll back or fray; also to provide this construction with such a lining for this purpose that it can be laundered in the usual way and will adhere in the process of ironing, to the ordinary lining of the collar from which it is entirely separated, thus adding to the stiffness of the collar points.

Other objects and advantages of the invention will appear hereinafter.

Reference is to be had to the accompanying drawings in which Fig. 1 is an illustration of a collar constructed in a preferred manner, shown as attached to a shirt, and illustrating the band and the collar in front elevation with the collar turned up from the band;

Fig. 2 is a similar view of the rear side of the same;

Fig. 3 is a fragmentary view of one point of the collar turned inside out to illustrate the stiffening means in full lines;

Fig. 4 is a view of the stiffening member;

Fig. 5 is a sectional view, taken at the top of Fig. 3, and looking downwardly; and

Fig. 6 is a perspective view of one end of the collar.

This invention can be applied to an attached or detached collar but it is particularly valuable in the attached variety. The collar itself is made in the usual way with a front layer 10 of the fabric which is to show in front attached to the band 11 in the usual way. This collar has a rear surface layer 12 attached to the rear layer 13 of the band. The collar is provided with a lining 14 just behind the front layer 10 and running with it throughout the length of the collar.

The rear member 12 is provided at each of the points with a stiffening member 15. This stiffening member is formed of comparatively coarse cloth but it may be of the same grade of material as the lining 14. It has the shape shown in Fig. 4, the point being cut off along the straight line 16 and

a notch 17 being provided in the edge which is to be bound into the seam 18 along the line 55 between the collar and the band. The edge 19 is sewed to the fabric 12 by a line of stitches 20 parallel with the edge preferably and this edge is not sewed to any other layer of the collar. Therefore it constitutes a part 60 of this rear layer of fabric. Naturally it is sewn in position with the parts turned wrong side out as shown in Figs. 3 and 5, or at least the parts are assembled in that 65 way.

It will be seen that the edge seams with which all collars are made, pass through the edges of the stiffener member 15 and that the seam 18 which connects the collar proper with the band also passes through the stiffener 15 near the edge having the notch 17. On account of these facts, this notch prevents the formation of a bunch at that point on the collar and the removal of the tip at 16 also prevents the same condition at the extreme point of the collar. The collar of course is turned right side out and can be ironed soft or starched semi-stiff or in the ordinary stiff manner. The ironing mats the two layers of coarse cloth 14 and 15 70 together throughout the surface of the stiffener member 15.

This forms a very stiff point, the stiffness of which is increased by the ironing operation. It is smooth throughout and presents 75 no appearance on the front of the collar that would indicate its presence. It is attached to the collar along part of the seam 18 and to the neck-band also at that point, so as to have a firm connection with the main part 80 of the collar.

Although we have illustrated and described only one form of the invention and shown it as attached to a shirt, we are aware of the fact that modifications can be made 85 and that it can be applied to a separate collar without departing from the scope of the invention as expressed in the claims. Therefore we do not wish to be limited to all the details of construction herein shown and 90 described, but what we do claim is:—

1. As an article of manufacture, a collar having a stiffening piece of fabric sewed into the inside thereof at the point, said fabric having the extreme point thereof cut 105 off short of the point of the collar and of

the intersection of the two edge seams of the collar.

2. As an article of manufacture, a collar having a stiffening piece of fabric sewed into the inside thereof at the point, said fabric having the extreme point thereof cut off short of the point of the collar and of the

intersection of the two edge seams of the collar and also having a notch cut in its upper edge at one end.

In testimony whereof we have hereunto affixed our signatures.

GEORGE W. JONES.
HARVEY D. ROBERSON.
